Primary Examiner — Michelle E. Wilson*Assistant Examiner* — Clese Moore, Jr.(57) **CLAIM**

The ornamental design for a wearable infant sleep apparatus, as shown and described.

DESCRIPTION

FIG. 1 is a front-top-left perspective view of a wearable infant sleep apparatus, showing my new design;

FIG. 2 is a rear-bottom-right perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof; and,

FIG. 8 is a bottom plan view thereof.

The broken lines shown in FIGS. 1, 3, and FIGS. 5-8 illustrate portions of the wearable infant sleep apparatus that form no part of the claimed design.
